THREAD CONTROL FOR WEFT
REPLENISHING LOOMS

Richard G. Turner, Worcester, Mass., assignor to
Crompton & Knowles Loom Works, Worcester,
Mass., a corporation of Massachusetts

Application December 11, 1951, Serial No. 260,973

11 Claims. (Cl. 139—256)

1

This invention relates to improvements in control mechanism for the thread of the bobbin which is transferred into the depleted shuttle of a weft replenishing loom during a bobbin changing operation.

Bobbin changing looms more particularly of the multicolor type generally employ a stationary magazine having stacks of reserve bobbins the threads or weft ends of which lead to a thread holder. The bobbin changing operation occurs as the lay is moving forwardly and the shuttle is picked approximately one-quarter of a pick or revolution of the crank shaft thereafter when the lay is at or near its top center position. At the time of picking it is desirable to have the thread of the freshly changed bobbin held by the thread holder in rear position favorable for self-threading of the shuttle when it is picked subsequent to replenishment. As the shuttle travels across the loom the thread from the new bobbin should pass under the fork of the center filling stop motion, but if the thread holder remains in rear position there is likelihood that the thread will be too far back to support the fork and the latter will cause unnecessary loom stoppage. To avoid this stoppage the thread holder should be returned to its forward position to move the thread under the fork, preferably prior to the end of the flight of the freshly replenished shuttle and when the lay is near its bottom center position.

Stationary magazines of the type already mentioned generally employ a setting shaft which, on a replenishing beat of the loom, is rocked from its normal position to a transfer or set position while the lay is between its top and bottom center positions at a time more than one beat of the loom prior to the aforesaid bottom center position of the lay when the thread holder should be returned to its front position. The driving shaft of the loom which reciprocates the lay completes a rotation each beat of the loom and because of its proximity of the thread holder it is desirable to have the forces for moving the holder derived from the crank shaft, but the driving shaft completes a rotation in less than the aforesaid time.

In order to utilize forces derived from the crank shaft to move the thread holder and utilize the setting shaft to initiate the thread holder moving operation it is an important object of the present invention to provide means whereby an indication given by the setting shaft when it rocks to set position can be stored until the time arrives in the operation of the loom when a one-pick cycle of movements of the thread holder can be started with assurance that it will be correctly

2

placed for shuttle threading. When this time arrives mechanism either operated or controlled by an actuator driven by the crank shaft becomes operative to effect movement of the thread holder first in a backward direction and then in a forward direction.

It is a further object of the invention to use an actuator in the form of a cam on the top or crank shaft to rock a cam lever connected to the thread holder which is pivoted for back and forth movement. The lever is normally out of alignment with the cam and is associated with resilient means in which energy is stored by the setting shaft when the latter moves to transfer position. The cam has high and low areas and the cam lever will be moved laterally against a part of the cam corresponding to a high area by a force derived from the setting shaft and transmitted through the resilient means. The latter then acts to move the lever into alignment with the cam when a low area of the cam arrives under an end of the lever. Thereafter the cam effects the aforesaid back and forth movements of the thread holder.

The setting shaft is generally returned to its normal position prior to completion of the movements of the thread holder and is not thereafter able to control the position of the lever. It is a still further object of the invention to provide the cam lever with a flange or the like which will hold the lever in alignment with the cam after the setting shaft returns to normal position.

In order that the invention may be clearly understood reference is made to the accompanying drawings which illustrate by way of example the embodiments of the invention and in which:

Fig. 2 is an enlarged plan view looking in the direction of arrow 2, Fig. 1,

Fig. 3 is an enlarged front elevation looking in the direction of arrow 3, Fig. 2, partly in section, showing the unit on which the cam lever and parts associated with it are mounted,

Fig. 4 is a horizontal section on line 4—4, Fig. 3, showing the cam lever in two different positions,

Fig. 5 is an enlarged rear elevation looking in the direction of arrow 5, Fig. 1, showing part of the stationary magazine with the aforesaid setting shaft in the normal position thereof.

Fig. 6 is a fragmentary side elevation, partly in section, looking in the direction of arrow 6,

Fig. 5.

Figs. 7 and 8 are diagrammatic views showing the cam lever in two positions with respect to the cam.

Fig. 9 is a diagrammatic side elevation showing the manner in which the cam and cam lever operate to move the thread.

Fig. 10 is a diagrammatic plan view of the lay showing the latter in two positions.

Fig. 11 is a side elevation of the actuator cam, the driving shaft on which it is mounted being shown in section.

Fig. 12 is a side elevation of the cam shown in Fig. 11, and

Fig. 13 is a diagrammatic view of parts of the magazine as viewed from the center of the loom with the parts in the positions they occupy during a bobbin transferring operation.

Referring to Figs. 1, 5 and 13, the loom frame 1 supports a multicolor reserve bobbin magazine M which in the present instance is provided with four vertical stacks of reserve bobbins indicated at 2. The loom has a lay 3 provided with a shuttle box 4 which receives, one at a time, the several self-threading shuttles which are used in the loom. One of these shuttles S is indicated in Fig. 1. The lay has a bunter 5 to engage a latch 6 pivoted to a transerrer arm 7 which is normally in raised position as shown in Fig. 1. The lay is also provided with the usual center filling stop motion fork F, and shuttle picking mechanism indicated at P in Fig. 1 is provided to pick the shuttle when the lay is at or near its top center position.

The loom has a top or crank shaft 10 which effects back and forth reciprocation of the lay by connectors one of which is shown at 11 in Fig. 1. This shaft rotates once for each beat of the lay and turns the lay successively through front, top, back and bottom center positions back to front center position to complete a one-pick cycle of the lay each beat of the loom. The loom is also provided with a bottom shaft 12 which rotates once for every second beat of the loom and gears 13 and 14 connect to the shafts.

Referring more particularly to Figs. 5 and 13, the magazine is provided with a fixed stud 15 on which is pivoted a shuttle position detector 16. The magazine is also provided with a setting shaft 17 having an operating shelf 18 secured thereto normally in the raised position shown in Fig. 5. This shaft 17 is connected to the latch 6 by well-known mechanism not shown herein effective when the shaft rocks from the normal to the set position thereof, counter-clockwise in Fig. 5, preparatory to a weft replenishing operation to lift the latch into the path of the bunter 5.

The magazine has a plurality of vertical slides one of which is shown at 20 in Fig. 5 and these slides are provided with dogs 21 pivoted at their upper ends. In Fig. 5 the slide is shown in its normal down position, but when a bobbin changing operation has been called the slide corresponding to the depleted shuttle will be raised and as it is subsequently depressed its dog will engage the shelf 18 to rock the shaft 17 to its transfer or set position one effect of which is to move the shuttle position detector 16 rearwardly, to the left in Fig. 13. Motion of detector 16 is effected by means of a vertical rod 25 attached at its upper end to an arm 27 secured to shaft 11. Movement of the setting shaft to its set position rocks the detector 16 in a clockwise direction as viewed in Fig. 13 so that the lower end 28 thereof moves rearwardly. This movement of the setting shaft 17 and the latch 6 to their transfer

positions and movement of the detector 16 to its rearward detecting position will ordinarily occur while the lay is between its top and bottom center positions immediately before the front center position of the lay on which the replenishing operation occurs a short time after the shuttle is picked from the opposite end of the loom from that shown in Fig. 1.

As the lay moves toward front center bunter 5 10 will engage the latch 6 to give the transerrer arm 7 a bobbin changing operation to replenish the shuttle S with a bobbin released from one or another of the stacks and designated herein at B, provided the shuttle is in proper position for transfer. During the latter part of the forward motion of the lay a wall 29 thereof behind the shuttle path will engage the lower end 28 of the detector 16 and rock the latter back to its normal position, thereby effecting return of the shaft 17 to its normal position by reason of arm 26 and connector 25. The return of the shaft 17 to its normal position ordinarily occurs when the lay has reached its front center position on a replenishing beat of the loom. If the shuttle should be misplaced the detector 16 is rocked back to its normal position to return shaft 17 to its normal position in time to permit the latch 6 to fall below the path of the bunter to cancel or revoke the bobbin changing operation.

The matter thus far described operates in the usual manner and has been set forth to provide an understanding of the relation between the timing of the mechanisms of the ordinary stationary magazine loom and the invention as set forth hereinafter.

In carrying the invention into effect the weft ends or threads W leading from the bobbins 2 in the magazine are attached to a thread holder member designated generally at H. When the previously mentioned bobbin B is transferred into the shuttle its thread, designated herein at W1 will move with the bobbin but will remain attached to the thread holder. In the present instance this holder is of the geared type and has front and back gears 30 and 31, respectively, between which the threads W extend and by which they are drawn away from the magazine and held taut. The thread holder member includes an arm 32 having a hub 33 pivoted on one of the tie rods 34 of the magazine, thus permitting the member H to occupy either front or back position in the loom. The hub 33 is limited as to its longitudinal position along the tie rod by collars 35. A stop member 36 is held by set screws 37 in angularly and longitudinally adjusted position on an extended end of the tie rod 34 and has front and back downwardly diverging arms 38 and 39 between the lower ends of which the thread holder supporting arm 32 extends. These diverging arms are provided with adjustable stop screws 40 to limit back and forth motion of arm 32.

A stand 45 is secured at 46 to a part 47 of the loom frame and has mounted therein a horizontal stud 48 which as shown herein is substantially parallel to the top or crank shaft 10. The operator means for the thread holder is mounted on this stud 48 and includes a cam lever designated generally at L. Lever L has a bearing 50 rockably mounted on the stud 48. A finger 51 on the bearing passes under a stop pin 52 fixed to stand 45 to limit counter-clockwise movement of the bearing and cam lever L as viewed in Fig. 1.

The bearing 50 has a vertical stud 53 on which

is pivoted a lever arm designated generally at 54. A stop finger 55 on arm 54 engages the stud 48 to limit rocking movement of the arm 54 in a counter-clockwise direction as viewed in Fig. 4. As shown herein arm 54 includes a strip 56 of sheet metal fixed with respect to bearing 50 and extending horizontally forwardly. The front end of strip 56 carries a stud 57 on which is rotatably mounted a roll 58. A guide flange 59 on stud 57 is of larger diameter than roll 58 and serves a purpose to be described.

A leaf spring 60 is secured at 61 to the bearing 50 and acts normally to hold the lever arm 54 in the position shown in full lines in Fig. 2, but this spring 60 is yieldable to permit the arm 54 and roll 57 to pivot around stud 53 to the dotted line position shown in Fig. 2. Extending upwardly from the bearing 50 is an arm 62 the upper end of which is connected to a cable 63 the forward end of which is connected as at 64 to the thread holder arm 32.

Secured to the top shaft 10 is a rotary cam or actuator member 65 having a low area 66, an incline 67, and a decline 68. The cam is relatively thin so that it will fit between lever arm strip 56 and flange 59, but under ordinary running conditions the cam will rotate without engaging the roll and the lever arm 54 and therefore the thread holder will remain at rest. A tension return spring 70 having one end 71 connected to the magazine and the other end 72 connected to the arm 32 tends normally to hold the latter forwardly against the forward stop screw 40 on diverging arm 38 to hold the thread holder member in its normal forward position, or to the left as shown in Fig. 1, but this spring will yield to permit the thread holder H to move rearwardly.

A controller means for the operating means, designated generally at C, operatively connects the lever arm 54 and the setting shaft 17. Included in this mechanism C is an arm 75 fixed with respect to shaft 17 and having a finger 76 adjustably connected thereto by bolts 77. The lower end of the finger 76 is below shaft 17 and has a stud 78 on which is pivoted a head 79 secured to the core 80 of a push-pull flexible wire designated at 81. This wire has a coiled spring shield 82 which is held in fixed position on the magazine by a clamp 83. The shield is held by a second clamp 84 mounted on the stop 36 and by a third clamp 86 fixed with respect to the loom frame, see Fig. 2. The core 80 has a second head 87 to which is connected one end of a tension energy storing spring 88 the other end of which is connected at 89 to the lever arm 54. Spring 88 is normally unstressed.

In operation, the parts will be in the normal position shown in Figs. 1 and 5 and in the full line position shown in Fig. 2. When a weft replenishing operation of the loom is indicated shaft 17 will rock to its set position and move finger 76, stud 78 and head 79 to the dotted line position shown in Fig. 5, thereby moving the core 80 to the right as viewed in Fig. 5 to cause head 87 to exert a pull on spring 88. As already mentioned this rocking of shaft 17 will occur when the lay is in the rear part of its reciprocation between its top and bottom center positions and at a time which is too early to start the back and forth motion of the thread holder. At this time the roll 57 will not be in register with the low area 66 of the cam but will register with a part of the cam on its side corresponding to a high area of the cam periphery. As spring 75

88 is pulled, therefore, the flange 59 will engage the side of the cam and spring 88 will be expanded and have energy stored in it.

As the cam continues to turn the low area 66 will arrive in lateral register with the roll 57 at approximately the time the lay is on its bottom center position, and at this time spring 88, which when expanded exerts a stronger force than does spring 60, will contract to move lever arm 54 so that roll 57 will align with the cam. The period of backward movement of the thread holder begins at this time, and as the cam continues to turn its incline will engage the roll 57 between flange 59 and lever part 56 to rock the lever L clockwise, Fig. 9, to move arm 62 rearwardly, or to the right as viewed in Fig. 9. Rearward movement of the thread holder will be completed at or about the time the lay reaches its top center position. When the lay reaches front center the shuttle will be replenished by a reserve bobbin and the setting shaft 17 will return to its normal position. The pull on spring 88 will therefore be slackened and leaf spring 60 will tend to return lever arm 54 to the full line position shown in Fig. 2, but the flange 59 will engage a side of the cam to hold the roll aligned with the cam.

By the time the thread holder has reached its rearmost position, see the dotted line position shown in Fig. 9, the freshly replenished shuttle will be picked by the picking mechanism P. The thread holder will now be in its rear position, see full lines Fig. 10, so that the thread W1 extending from the thread holder to the replenished shuttle will be favorably placed for self-threading of the shuttle when the latter is picked. The lay will continue to move rearwardly as the shuttle moves along it and these parts will be as shown in dotted lines, Fig. 10, at some later time in the operation of the loom.

As the cam continues to turn the roll will move down the decline of the cam and enable spring 70 under control of the cam to return the thread holder to its front position, at which time the thread W1 will be moved under the center filling stop motion fork F when the lay is at or near bottom center, and preferably while the shuttle is still in flight. By this time low area 66 will be under roll 57 and leaf spring 60 will be able to return lever arm 54 to its normal position shown in full lines, Fig. 2.

From the foregoing it will be seen that the invention sets forth simple means by which a driving shaft of the loom can be utilized to move the thread holder rearwardly to facilitate threading of a freshly replenished shuttle and then forwardly to move the thread under the fork of the filling stop motion. The operation is initiated by rocking of the setting shaft to its transfer or set position, and a resilient element, such as spring 88, in which energy derived from the setting shaft can be stored permits a delay in the time at which rocking of the cam lever L is begun by the cam until the back and forth movements of the thread holder can be completed in a one-cycle period. The setting shaft remains in its set position long enough to enable the incline on the cam to begin the up motion of roll 57 and by the time the setting shaft is returned to its normal position the flange 59 will hold the roll 57 aligned with the periphery of the cam until the low area of the cam again arrives under the roll. This feature of continued rocking of lever L after resetting of

shaft 17 is not limited to a one-pick cycle of operation of the loom shaft. The spring 88 is stronger than spring 60 and overpowers it when the low area of the cam arrives in register with the roll. The spring 10 which moves the thread holder forwardly from its rear position also acts to hold the roll against the periphery of the cam. Return of the thread holder to its front position by spring 70 is controlled by the cam. While the setting shaft has been described herein as returning to its normal position when the lay is on front center, certain features of the invention are not necessarily restricted to this time of resetting of the setting shaft.

Having now particularly described and ascertained the nature of the invention and in what manner the same is to be performed, what is claimed is:

1. In a weft replenishing loom having a center filling stop motion fork and a self-threading shuttle which on a replenishing operation of the loom is replenished by a bobbin from which a thread extends, a shaft which rotates during loom operation, an actuator member secured to and turning with said shaft, a thread holder member to which the thread is attached mounted to be located either in front or back position in the loom, operator means for the thread holder member having a part thereof permanently connected in operative relation with respect to one of said members and having another part thereof capable of operative relation with the other member but normally inoperatively related to said other member, a setting shaft which moves from the normal position thereof to set position preparatory to said replenishing operation, and means controlled by said setting shaft operative incident to movement of the latter to the set position thereof to effect operative relation of said other part of said operator means with the other member, the actuator member being so constructed that it thereupon cooperates with said operator means to effect movement of the thread holder to the back position thereof to place said thread favorably for self-threading of the shuttle when the latter is picked subsequent to replenishment thereof, and means thereafter effective to move the thread holder forwardly to move the thread under said filling stop motion fork.

2. In a weft replenishing loom having a center filling stop motion fork and a self-threading shuttle which on a weft replenishing operation of a loom is replenished by a bobbin from which a thread extends, a thread holder to which the thread is attached mounted for back and forth motion in the loom, a shaft which rotates during loom operation, actuator means rotated by the shaft, a setting shaft which moves from the normal position thereof to set position preparatory to said replenishing operation, operator means controlled by the setting shaft effective due to movement of the setting shaft to the set position thereof to cause the actuator means in cooperation with the operator means to move the thread holder rearwardly to position said thread favorably for self-threading of the shuttle when the latter is picked subsequent to replenishment thereof, and means thereafter effective to move the thread holder forwardly to locate the thread under said filling fork.

3. In thread control mechanism for a weft replenishing loom having a lay provided with a center filling stop motion fork and having a self-threading shuttle which on a weft replenishing

operation of the loom is replenished by a bobbin from which a thread extends, a shaft moving the lay successively through front, top, back and bottom center positions each beat of the loom, means 5 to pick the shuttle subsequent to said replenishing operation when the lay is approximately on the next top center position thereof, a thread holder to which the thread is attached capable of occupying either front or back positions in 10 the loom, a rotary actuator driven by said shaft, a setting shaft moving from the normal position thereof to set position thereof preparatory to said replenishing operation while the lay is between its top and bottom center positions on the beat of 15 the loom in which said replenishing operation occurs, means controlled by said setting shaft and operated by said actuator effective due to movement of the setting shaft to the set position thereof to begin movement of the thread holder 20 rearwardly when the lay is approximately on the bottom center position thereof and complete said movement of the thread holder when the lay is approximately on the top center position thereof to move the thread to a rear position 25 favorable for self-threading of the shuttle when the latter is picked subsequent to said replenishing operation, and means thereafter effective by the time the lay next reaches approximately the bottom center position thereof to move the thread holder forwardly to move the thread forwardly 30 under said filling fork.

4. In thread control mechanism for a weft replenishing loom having a lay provided with a center filling stop motion fork and having a self-threading shuttle which on a weft replenishing operation of the loom when the lay is approximately on the front center position thereof is replenished by a bobbin from which a thread extends, a driving shaft which moves the lay 35 successively through front, top, back and bottom center positions each beat of the loom, a cam secured to and rotating with the shaft once each beat of the loom, means to pick the shuttle subsequent to said replenishing operation when the lay is next on approximately the top center position thereof, a thread holder to which said thread is attached capable of being either in front or back position in the loom, a setting shaft moving from the normal position thereof to set position 40 thereof preparatory to said replenishing operation when the lay is between the top and bottom center positions on the beat of the loom when said replenishing operation occurs, operator means connected to the thread holder 45 normally out of operative relation relative to said cam, and means controlled by said setting shaft effective incident to movement of the latter to the set position thereof to move said operator means into operative relation with respect 50 to the cam when the lay is substantially on the bottom center position thereof on the beat of the loom in which said replenishing operation occurs, said cam thereafter effective in cooperation with the operator means to move the thread holder to the back position thereof to locate said thread favorably for self-threading of the shuttle when the latter is picked subsequent to said replenishing operation, and means thereafter effective to return the thread holder to the front position 55 thereof by the time the lay next reaches substantially the bottom center position thereof to move the thread under the fork, and means thereupon effective to move the operator means to a position out of operative relation with respect 60 to the cam.

75 spect to the cam.

5. The structure set forth in claim 4 wherein said means controlled by the setting shaft includes a resilient element in which energy derived from the setting shaft is stored between the time the setting shaft moves to the set position thereof and the next following bottom center position of the lay, said element due to the energy stored therein being effective to move the operator means into operating position relative to said cam.

6. The structure set forth in claim 4 wherein means operating upon return of the thread holder to the front position thereof moves the operator means to a position out of operative relation with respect to the cam.

7. In thread control mechanism for a weft replenishing loom having a lay provided with a center filling stop motion fork and having a self-threading shuttle which on a weft replenishing operation of the loom is replenished by a bobbin from which a thread extends, a shaft which moves the lay successively to front, top, back and bottom center positions each beat of the loom, means to pick the replenished shuttle when the lay is substantially on the top center position thereof subsequent to said replenishing operation, a thread holder to which said thread is attached mounted to be located either in front or back position in the loom, a cam having high and low areas driven by said shaft, operator means connected to the thread holder normally out of operative relation with respect to said cam, a setting shaft which preparatory to said replenishing operation moves from the normal position thereof to set position when the lay is between the top and bottom center positions thereof on the beat of the loom on which the replenishing operation occurs, said setting shaft returning to the normal position thereof subsequent to arrival of the lay at the bottom center position thereof on the beat of the loom in which said replenishing operation occurs and prior to picking of the replenished shuttle, and means controlled by the setting shaft operative incident to movement of the setting shaft to the set position thereof to move the operator means over the low area of the cam when the loom is substantially on the bottom center position thereof, whereupon said cam causes the operator means to move the thread holder to the back position thereof to locate said thread favorably for self-threading of the replenished shuttle when the latter is picked subsequent to return of said setting shaft to the normal position thereof, and resilient means effecting forward movement of the thread holder subsequent to picking of the replenished shuttle to move said thread under said filling fork.

8. In thread control mechanism for a weft replenishing loom having a lay provided with a center filling stop motion fork and having a self-threading shuttle which on a weft replenishing operation of the loom is replenished by a bobbin from which a thread extends, a shaft turning to move the lay successively through front, top, back and bottom center positions each beat of the loom, means to pick the shuttle subsequent to said replenishing operation when the lay is next on approximately the top center position thereof, a cam having high and low areas rotated by said shaft, a thread holder to which the thread is attached mounted to be located either in front or back position in the loom, operator means connected to the thread holder normally inop-

eratively related with respect to the cam, a setting shaft moving from the normal position thereof to set position thereof when the lay is between the top and bottom center positions thereof on the beat of the loom in which said weft replenishing operation occurs, said setting shaft returning to the normal position thereof when the lay is substantially on the front center position thereof during said weft replenishing operation, means

5 controlled by the setting shaft effective incident to movement of the latter to the set position thereof to move the operator means over said low area and into operative relation with respect to said cam, the latter thereupon causing the operator means during a period beginning prior to return of the setting shaft to the normal position thereof and continuing after said setting shaft returns to its normal position to move the thread holder to the back position thereof to place said thread favorably for self-threading of the shuttle when the latter is picked subsequent to said replenishing operation, means maintaining the operator means in operative relation with respect to said cam subsequent to return of the setting shaft to the normal position thereof, and means effective subsequent to picking of the replenished shuttle to effect forward movement of the thread holder to move the thread under said filling fork.

30 9. In thread control mechanism for a weft replenishing loom having a center filling stop motion and a self-threading shuttle which on a weft replenishing operation of the loom is replenished by a reserve bobbin from which a thread extends, the replenishing operation occurring when the lay is on the front center position thereof and the loom thereafter effecting picking of the shuttle when the lay is at or near its top center position, a thread holder to which the thread is attached, means mounting the thread holder for movement either to back or forward position, return means normally holding the thread holder in forward position, a setting shaft 35 rocking from the normal position thereof to set position when the lay is in rearward position prior to said replenishing operation, a cam rotating once for each one pick cycle of the loom having high and low areas, a cam lever mounted for angular motion on the loom having an arm operatively connected to the thread holder and having another arm normally inoperatively related to the cam but movable into operative position relative to said cam, and a controller for said other arm including a resilient element connected to the setting shaft effective upon movement of the latter to the set position thereof to move said other arm laterally against a part of the cam corresponding to the high area thereof and store energy in said element, continued turning of the cam causing the low area thereof to register with said other arm, whereupon said element effects alignment of said other arm with the cam and the latter thereupon causes the cam 40 lever to move the thread holder to the back position thereof to locate the thread favorably for self-threading of the replenished shuttle when the latter is picked, said return means being thereafter effective to move the thread holder forwardly subsequent to picking of the shuttle to effect movement of the thread under the filling stop motion fork.

45 10. The thread control mechanism set forth in claim 9 wherein said return means acts through said one arm of the cam lever to hold said other

arm against the cam while the high area of the latter engages said other arm.

11. The thread control mechanism set forth in claim 9 wherein said other arm is pivoted on the cam lever and a spring normally holds said other arm out of operative position relative to the cam and said element is a second spring strong enough to overpower the first spring.
